UNITED STATES PATENT OFFICE

BERNARD O. ANDERSON, OF EAST MCKEEFORT, PENNSYLVANIA

HOT AIR DEFLECTOR

Application filed March 26, 1932. Serial No. 601,346.

The present invention relates to a hot air deflector for hot air heating systems which usually have connection with a room through an opening in the floor or wall thereof and has for some of its objects to provide, in a manner as hereinafter set forth, a deflector of this character which will be simple in construction, strong, durable, efficient and reliable in use, attractive in appearance, and which may be manufactured and installed at low cost.

Another important object of the invention is to provide a hot air deflector through the medium of which the air in a room will be caused to circulate in such a manner to materially reduce the accumulating of dirt, dust, lint, etc. on the walls and ceiling of said room.

Another very important object of the invention is to provide a hot air deflector of the character described embodying a novel construction, combination and arrangement of parts through the medium of which the air of the room in which the deflector is installed will be moistened.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in front elevation of a hot air deflector constructed in accordance with the present invention.

Figure 2 is a view in vertical longitudinal section through the deflector.

Figure 3 is a view in horizontal section, taken substantially on the line 3—3 of Figure 2.

Figure 4 is a view in horizontal section, taken substantially on the line 4—4 of Figure 2.

Figure 5 is a detail view in rear perspective of the water pan holder and hood.

Figure 6 is a detail view in perspective of the damper.

Figure 7 is a fragmentary view in vertical

section through a portion of the top of the cabinet.

Figure 8 is a detail view in perspective of the water pan.

Referring now to the drawings in detail, it will be seen that the embodiment of the invention which has been illustrated comprises a cabinet designated generally by the reference numeral 1, said cabinet being of any suitable material, preferably metal, and including integral front and side walls 2 and 3, respectively, a back or rear wall 4 secured, as at 5, to the side walls 3, and a removable top which is designated generally by the reference numeral 6. The vertical corner portions of the cabinet are formed to enhance the appearance of said cabinet, as at 7. Of course, the cabinet may be otherwise ornamented in any suitable manner.

The top 6 includes the spaced upper and lower sheets 8 and 9, respectively, having the abutting downturned skirt portions 10 and 11, respectively, the portion 10 terminating in an internal, upturned flange 12 engaged with and retaining the portion 11. Thus, a depending flange is provided which encircles the upper portion of the walls of the cabinet which provides an attractive fit for the top. Between the sheets 8 and 9 of the top there is disposed a filler 13, preferably of heat insulating material.

The lower portions of the walls of the cabinet 1 are spaced above the floor 14 to provide the air inlet openings 15 at the lower end of the cabinet. Thus, the corner portions 7 project below the cabinet walls and constitute supporting legs for the cabinet. The front wall 2 of the cabinet is provided, in its upper portion, with an outlet opening 16. The marginal portions of the material of the front wall 2 around the opening 16 are folded inwardly upon said front wall to provide the flanges 17 which, in turn, are cut and bent to provide the oppositely disposed flanges or retainers 18 in which a perforated plate 19 is mounted.

A vertical inlet pipe is designated by the reference numeral 20, said pipe being preferably rectangular in horizontal section and being engageable in the usual opening 21.

provided in the floor 14. The pipe 20, of course, rises from the floor 14 in the cabinet 1. The lower portion of the pipe 20 is formed to provide an external supporting flange 22 engageable with the floor 14 and the upper portion of said pipe 20 is formed to provide the comparatively small external flange 23 upon which rests the enlarged lower portion 24 of a vertical conduit which is designated generally by the reference numeral 25. The rear wall 4 of the cabinet 1 also constitutes the rear wall of the conduit 25. The conduit 25 is closed at its upper end, as at 26, the end 26 having an upturned flange 27 abutting the rear wall 4 of the cabinet. In the upper portion of its front, the conduit 25 is provided with an outlet passage 28 around which the material of said conduit is bent inwardly upon itself, as at 29.

20 A damper 30 is rotatably mounted in the pipe 20 on the pintles 31 secured thereto and journaled in said pipe, one of said pintles being angular to provide an adjusting handle 32. As best seen in Figure 4 of the drawings, 25 a small coil spring 33 encircles the other pintle 31 and is engaged with the damper 30 for yieldingly urging said damper against one wall of the pipe 20 and in this manner the damper is frictionally retained in adjusted 30 position. The damper 30 is operable by inserting a hand through the side opening 15 in the lower portion of the cabinet 1 which is adjacent the handle 32.

35 Mounted horizontally on an intermediate portion of the conduit 25 at a point spaced below the passage 28 is a shelf 34 having a front 35 and sides 36, said sides 36 projecting rearwardly adjacent the sides of the conduit 25 and being rigidly secured thereto by any 40 suitable means, as at 37. Thus, the shelf 34 is securely mounted in position on the conduit 25. The shelf 34 is spaced from the front and side walls of the cabinet 1 to provide air passages therebetween. Further, the conduit 25 45 is also spaced from the front and side walls of the cabinet for the vertical passage of air. Flanges 38 are provided on the upper portions of the side walls 36 and are formed to define channels for the reception of the end portions 50 of a substantially U-shaped hood 39, said hood 39 being readily removable when the top 6 of the cabinet is removed. The hood 39, when in position, is engaged against the upper portion of the conduit 25, as illustrated to 55 advantage in Figure 2 of the drawings. An external flange 40 is provided on the rear portion of the hood 39. The reference numeral 41 designates a handle on the top of the hood 39. The hood 39 is positioned to the 60 rear of the perforated plate 19 and is spaced therefrom. The shelf 34 is adapted to hold a water pan 42 to which access may be conveniently had for filling by simply removing the top 6 and the hood 39.

65 In case the hot air opening from the heat-

ing plant to the room is through a wall instead of a floor, the pipe 20 is positioned as indicated in broken lines in Figure 2 of the drawings, the rear wall 4 of the cabinet 1 being provided with an opening for the 70 reception of one end portion of said pipe 20. This is permitted by reason of the fact that the conduit 25 is mounted on the rear wall of the cabinet and secured, as at 43. Of course, when the device is thus installed, the 75 lower end of the conduit 25 may be closed.

As will be obvious, the heated air passes upwardly in the conduit 25 and is directed forwardly through the passage 28, through the hood 39 immediately above the water pan 42 and then passes through the perforated plate 19 into the room. Cold air is drawn into the cabinet from the room through the openings 15 and passes upwardly around the conduit 25 and is returned to the room 80 through the perforated plate 19 and the opening 16.

The upper portions of the walls of the cabinet 1 are turned inwardly to provide the 85 horizontal supporting flanges 44 on which the top 6 rests. At their lower ends, the supporting legs of the cabinet are turned inwardly, as at 45 (See Figures 3 and 4 of the drawings).

It is believed that the many advantages of a hot air deflector constructed in accordance with the present invention will be readily understood, and although the preferred embodiment of the invention is as illustrated and described, it is to be understood that changes 90 in the details of construction and in the combination and arrangement of parts may be resorted to which will fall within the scope of the invention as claimed.

What is claimed is:—

1. A hot air deflector comprising a cabinet having an outlet opening in the upper portion of its front, a conduit mounted in the cabinet having an outlet passage therein aligned substantially with the outlet opening, said conduit being connected with a source of hot air supply, a support mounted on the conduit below the outlet passage therein and projecting horizontally therefrom toward the front of the cabinet, and a substantially U-shaped hood mounted on the support.

2. A hot air deflector comprising a cabinet having an outlet opening in the upper portion of its front, a conduit mounted in the cabinet having an outlet passage therein aligned substantially with the outlet opening, said conduit being connected with a source of hot air supply, a support mounted on the conduit below the outlet passage therein and projecting horizontally therefrom toward the front of the cabinet, a substantially U-shaped hood mounted on the support, and a receptacle mounted on the support for the reception of water, the hood 130

defining a passage for conducting the air from the conduit toward the outlet opening of the cabinet above the receptacle.

3. A hot air deflector comprising a cabinet 5 having an outlet opening in the upper portion of its front, a conduit mounted in the cabinet having an outlet passage therein aligned substantially with the outlet opening, said conduit being connected with a 10 source of hot air supply, a support mounted on the conduit below the outlet passage therein and projecting horizontally therefrom toward the front of the cabinet, a substantially U-shaped hood mounted on the support, 15 and a receptacle mounted on the support for the reception of water, the hood defining a passage for conducting the air from the conduit toward the outlet opening of the cabinet above the receptacle, the conduit and 20 the hood being spaced from the front and side walls of the cabinet to provide vertical air passages, said cabinet further having air inlet openings in its lower portion.

4. A hot air deflector comprising a cabinet 25 including a removable top, said cabinet having air inlet openings in its lower portion and further having an air outlet opening in the upper portion of its top, a conduit mounted vertically in the cabinet and having 30 its outlet passage therein aligned with the outlet opening, a pipe connecting the conduit with a source of hot air supply, a horizontal shelf rigidly mounted on the conduit between said conduit and the cabinet front, a 35 water receptacle mounted on the shelf, and a substantially U-shaped hood removably mounted on the shelf over the water receptacle.

In testimony whereof I affix my signature.
40 BERNARD O. ANDERSON.
